UNITED STATES PATENT OFFICE

RALPH E. DENDLER, OF BERWICK, PENNSYLVANIA, ASSIGNOR TO AMERICAN CAR AND FOUNDRY COMPANY, OF NEW YORK, N. Y., A CORPORATION OF NEW JERSEY

MINE CAR

Application filed April 6, 1931. Serial No. 527,987.

This invention relates to mine cars and has for one object the provision of a low height mine car of great lading capacity.

Another object of this invention is the provision of a mine car having a body supported by drop axles.

Still another object of this invention is the provision of a mine car having a body resting upon and supported by drop axles, the latter being positioned and retained by journal boxes and being free of direct connection with the body to permit the easy and quick separation of the body and axles should occasion demand.

15 A further object of this invention is the provision of a mine car having a body supported on drop axles, the body including a car bottom comprising a central floor portion and side floor portions, the central floor portion being arranged above the main portion of the axles but being positioned below the spindle portions of the axles whereby to provide for increased lading capacity, and the side floor portions being so arranged as 20 to intersect the plane of the tops of the car wheels.

A still further object of this invention is the provision of a new and improved mine car body construction.

30 Other objects and advantages of this invention will be apparent from the following description taken in conjunction with the accompanying drawings in which:

35 Figure 1 is a longitudinal sectional view through a portion of the car at one end thereof.

40 Fig. 2 is a side elevation of the opposite end of the car, certain parts being shown in section and other parts being shown broken away.

Fig. 3 is an end view of the car at the gate end thereof.

Fig. 4 is a sectional view on the line 4—4, Fig. 5 and

45 Fig. 5 is a fragmentary top plan view of the car; the view showing one end of the car and a portion of the opposite end, certain parts of the car being shown in section.

50 Referring now more particularly to the drawings in which similar characters of ref-

erence designate similar parts in the several views, the car of the present invention comprises a body indicated generally at A mounted on and supported by drop axles B, on the spindles 2 of which the wheels 6 are mounted for rotation.

The body A has a lower portion composed of a metal bottom 8 and side sills 10 formed integral therewith, the side sills having outwardly directed flanges 12 for supporting the side floor portions 14. As shown clearly in Fig. 4 the side floor portions are substantially horizontal and intersect the plane of the tops of the wheels 6; said wheels projecting through openings formed in the side floor portions and covered by wheel hoods 16 riveted to the side floor portions and the flanges 12 as shown at 18. If desired, the wheel hoods 16 may be of such form as to extend to and be riveted or otherwise connected to vertical side walls 20 which are preferably formed integral with the side floor portions 14 and which extend vertically upward therefrom. For stiffening the side walls, beads 22 are formed along the upper edges thereof.

The car of the present invention is designed for end dumping and hence is provided with a fixed end wall 24 at one end of the car body and an end gate 26 at the opposite end of the body pivoted for swinging movement as shown at 28. Obviously within the spirit of the present invention, the body may be designed for rotary dumping purposes in which event the body may be provided with fixed walls at each end thereof.

From the description thus far it can be seen that the body of the present invention includes a metal bottom which may be a single sheet of metal, or a plurality of sheets if desired, the side edges of said metal sheet being offset to define side floor supporting portions or flanges 12, the offsets forming the body side sills 10. In the instance shown the offsets each include upwardly extending diagonal portions 30 and vertically arranged portions 32 with which latter the flanges 12 are formed; the offsets being formed integral with the bottom plate eliminating the necessity of using independent sill members such as commercial channels, I-beams and the

like, and the diagonal portions 30 providing for increased lading capacity of the body as will be obvious.

- 5 For stiffening the body, ties 34 are provided intermediate the ends of the body, which extend along the under surfaces of the bottom and along the side sills 10 and side floor portions 14 and then upwardly along the side walls 20; suitable fasteners 10 such as rivets 36 being provided for securing the ties to the body. The ties may be, if desired, longitudinally ribbed or corrugated as shown at 38 (see Fig. 5) though this is merely by way of example. For further 15 stiffening the body, stiffeners 39 are provided adjacent each end of the body which extend from the side sills 10 outwardly under the side floor portions and then upwardly along the vertical side walls 20 (see Fig. 5).
- 20 At each end of the car an end sill is arranged, the same comprising a Z section 40, the upper flange 42 of which is of substantial width and projects outwardly from the end wall 24 and end gate 26, respectively. As 25 shown clearly in Figs. 1 and 5 the opposite ends of the car bottom 8 underlie the lower flanges 44 of the end sills and are secured thereto by suitable fasteners 46, the latter also serving to secure under bumper plates 48 30 forming part of the end bumpers of the car. The bumpers each include a filler block 50 mounted on the plates 48 and provided with a top bumper plate 52 riveted as at 54 to the web 56 of the end sill, the rivets 54 at one end 35 of the car also serving to secure and fasten the before mentioned fixed end wall 24 to the adjacent end sills as clearly shown in Fig. 1. The bumpers each include a front plate 58 which overlaps the top and bottom plates 40 and 48 respectively. The upper flange 42 of the respective end sills also serves as part of a coupling member to receive a coupling pin 60 which extends therethrough and through a coupling plate 62 and through the 45 bumper, all as clearly shown in Figure 1. For stiffening the end wall 24 spaced diaphragms 64 are provided which are secured to said end wall and to the upper flange 42 of the end sill.
- 50 As before mentioned the car of the present invention is designed for end dumping and to permit easy discharge of the lading from the car body, an end slope sheet 66 is provided which is riveted to the car bottom 8 55 and which extends upwardly from the bottom at an incline and its forward edge substantially abuts the upper edge of the web 56 of the adjacent end sill and is welded thereto as shown at 68. The sheet 66 is of 60 such form as to nicely fit between the side sills 10 and the side edges thereof are connected to said sills, preferably by welding, as shown at 67. For providing additional support for the slope sheet 66, a diaphragm 70 is secured 65 to the bottom 8 and end sill by fasteners 72

and 73 respectively; said diaphragm being arranged longitudinally of the body and having an upper supporting flange 75 upon which the slope sheet 66 rests. If desired, openings may be formed in the slope sheet 70 66 to permit direct connection thereof with the flange 75 by weld metal.

To stiffen the car body at the junction of the side sills, end walls and bottom, corner angles 74 are provided which are attached to the body and end sills by suitable fasteners such as rivets 76. As before mentioned herein the body is supported on drop axles, but said body is not secured directly to said axles in order that the body and axles may be easily separated to permit replacement of parts. The body is provided with axle brackets 78 which are secured to the side sills and which embrace the trunnion portions 80 of the axles, thereby mounting the 80 axles in what might be termed a floating manner relative to the car body. The axle brackets may be of any preferred or desired construction, but as shown in the drawings they include the attaching portion 82 which 85 conforms to the shape of the side sills to fit against the diagonal and vertical portions 30 and 32, respectively; said attaching portions being slotted to permit removal and replacement of the axles therein. Adjacent 90 the slots in the attaching portions 82, the axle brackets are provided with ribs 84 for stiffening purposes, which ribs extend upwardly to a point such that they underlie the flanges 12 of the sills 10 and serve to stiffen said flanges as will be apparent. For retaining the axles, retaining pins 86 are provided which are removably positioned between adjacent ribs 84 of each bracket.

From the above description it is believed 105 that the construction of the car of the present invention will be fully apparent to those skilled in the art. It is to be noted that the car of the present invention is of low height and yet provides for an extreme lading 110 capacity. The car is also devoid of independent elements such as channels, I-beams or Z-bars for body sills inasmuch as the sill members are formed as integral parts of the bottom portion of the car body; said bottom portion being, in effect, pan-shaped and comprising a metal bottom portion, the side edges of which are offset to define the body sills, and the offset portions provide supporting flanges for the side floor portions which form 115 a part of the upper portion of the car body. It will also be apparent that replacement of parts is easily and quickly effected by removal of the pins 86 to permit removal of the body from the axles; the body being free of direct attachment to the axles.

The drawings herein illustrate one embodiment of the invention, but it is to be understood that they are for illustrative purposes only and various changes in the form 120

and proportions of the construction shown may be made within the scope of the appended claims without departing from the spirit of the invention.

5 What is claimed is:

1. A mine car comprising a body having a lower section composed of a bottom and side sills formed as a unitary structure, and an upper portion including side floor portions extending laterally from the sills, upper side walls, axle brackets secured to the sills, a pair of drop axles extending through said brackets and on which the body is removably mounted, and wheels mounted on the axles and projecting through the side floor portions, said central floor portion being mounted above the axles and intersecting the plane of the lower part of the wheels.

2. A mine car comprising a body having a lower portion composed of a central floor portion and side sills formed as a unitary structure, and an upper portion composed of side floor portions secured to the side sills and having side walls rising therefrom, axle brackets secured to the side sills and engaging the side floor portions to stiffen the latter, a pair of drop axles on which the body rests, said axles extending through the brackets whereby the body and axles are detachably connected together, wheels on the axles projecting through the side floor portions, hoods covering the projecting portions of the wheels, and belts secured to the side walls and extending under the body and connected thereto.

3. In a mine car, a body comprising a lower portion composed of a plate metal bottom having its side edges offset to define side sills and supporting flanges, side floor portions secured to the supporting flanges and arranged substantially parallel to the bottom, and side walls rising vertically from the side floor portions.

4. In a mine car, a body comprising a lower portion composed of a plate metal bottom having its side edges offset to define side sills and supporting flanges, the offsets including diagonal and vertical portions, an upper portion comprising unitary members secured to the supporting flanges and comprising side floor portions arranged substantially parallel to the plate metal bottom and side walls rising vertically therefrom.

5. A mine car comprising a body having side walls, side floor portions, a central floor portion having its side edges offset to define side sills and supporting flanges to which latter the side floor portions are secured, axle brackets connected to the offsets, a pair of drop axles extending through the brackets and on which the body rests, said axles being free of direct connection with the body, and wheels rotatably mounted on the axles and projecting through the side floor portions.

6. In a mine car, the combination with

drop axles of a combined central floor portion and side sills formed as a unitary structure supported by the axles and detachably connected to said axles in such a manner as to be freely removable therefrom.

7. In a mine car, the combination with drop axles of a combined central floor portion and side sills formed as a unitary structure removably supported by the axles and being free of direct connection therewith.

8. In a mine car, the combination of U-shaped axles, a body including a combined plate metal central floor portion and side sills formed as a unitary structure mounted on the axles, and brackets secured to the side sills and embracing parts of the axles for providing the connecting means for the body and axles.

9. In a mine car, the combination of U-shaped axles, a body resting on the axles and including a central floor portion and side sills formed integral therewith, brackets secured to the side sills and embracing the axles to detachably connect the axles to the body, said central floor portion being continuous from end to end of the body, an end gate, and a bottom slope sheet secured to the bottom and side sills and rising upwardly at an incline toward the end gate.

10. In a mine car, wheels, U-shaped axles, a body resting upon the axles and including a central floor portion and side sills formed as a unitary structure, said central floor portion being arranged in a plane above the axles and intersecting the plane of the lower portions of the wheels, brackets secured to the sills and embracing parts of the axles to detachably connect the latter to the body, a fixed end wall, an end gate, and a slope sheet secured to the bottom and rising upwardly at an incline toward the end gate.

11. In a mine car, the combination of a lading body, side sills formed as an integral part of the lading body, U-shaped axles having portions thereof arranged in a plane lower than the bottom of the lading body and having other portions arranged adjacent the side sills, brackets secured to the side sills and embracing the axles whereby to detachably connect the axles and body, wheels projecting into the lading zone of the body, an end gate, and a slope sheet secured within the lading zone and inclining upwardly toward the end gate.

12. In a mine car, a body comprising a lower portion composed of a continuous plate metal bottom and side sills formed integral therewith, a Z-bar end sill having its lower flange inwardly extended and secured to said bottom and its upper flange outwardly projected to define a coupler member, an end gate pivoted to the body and a slope sheet secured to the bottom and side sills and inclining upwardly from the bottom, the forward edge of said sheet being arranged adjacent the junc-

ture of the web and upper flange of the end sill and being connected thereto.

13. In a mine car, a body, drop axles on which the body is mounted, brackets secured to the body and embracing portions of the axles to detachably connect said body and axles, a Z-bar end sill having its upper flange projecting outwardly from the body and defining a coupler part, a bumper secured to the end sill in spaced relation with respect to said upper flange, an end gate pivoted to the body, and an end slope sheet secured to the car bottom and inclined upwardly toward the end gate with its forward edge in substantially abutting relation with the end sill at the juncture of the top flange and web thereof, said forward edge being welded to said end sill.

14. A mine car comprising a body having a lower section composed of a bottom and side sills formed as a unitary structure, the said side sills having out-turned flanges along their upper edges, and an upper portion including side walls and side floor portions supported on and secured to the said out-turned flanges, axle brackets secured to the side sills, a pair of drop axles extending through the brackets and on which the body is removably mounted, and wheels on the axles projecting through the side floor portions, said central floor portion being mounted above the axles and intersecting the plane of the lower part of the wheels.

In witness whereof I have hereunto set my hand.

RALPH E. DENDLER.
